N. Y., a corporation of New York

Application July 11, 1956, Serial No. 42,217

Term of patent 14 years

(Cl. D56—4)

Fig. 1 is a perspective view of a portable phonograph showing my new design, in carrying position.

Fig. 2 is a perspective view of the lid of the phonograph open, disclosing the ornamental details of its slanted grille;

Fig. 3 is a side elevation;

Fig. 4 is a front elevation; and

Fig. 5 is a top plan view.

Characteristic features of my inventive design are shown by the full lines of the drawings.

I claim:

The ornamental design for a portable phonograph, substantially as shown and described.
